UNITED STATES PATENT OFFICE.

THOMAS C. WHITEHEAD, OF DETROIT, MICHIGAN.

PUMP.

Application filed July 23, 1923. Serial No. 653,233.

The invention relates to pumps, being more particularly designed for use in gas compressors, and the invention consists in the construction as hereinafter set forth.

5 In the drawings:—

Figure 1 is a side elevation partly in section;

Figure 2 is an end elevation partly in section;

10 Figure 3 as a plan view taken on the line 3—3 of Figure 1.

In the construction of pumps for the purpose described, it is desirable to have a noiseless valve action and also a construction where the inlet port will automatically open even where pumping from comparatively high vacuum. Valves which are held to their seats either by gravity or by other resilient pressure often fail to operate when pumping from high vacuum, inasmuch as there is not sufficient gaseous pressure to raise the valve from its seat. This defect I have overcome by a valveless control of the inlet port. On the other hand, for retaining the compression pressure, I have provided an automatically seating valve, the construction being as follows:—

A is the cylinder block, which, as shown, has a plurality of cylinders B therein. C is a common head for the cylinders. D is a plate clamped between the head C and the block A. E is a piston for each of the cylinders, which has a passage F extending longitudinally therethrough and communicating with the lateral port G, which, at the completion of the suction stroke, registers with an inlet port H in the wall of the cylinder. I are ports in the plate D opposite each cylinder. J are segmental recesses in the head opposite each port I, and K are resilient strips forming valves which are arranged in the recesses J and normally lie flat to seat upon the plate D surrounding the ports I.

45 With the construction as described, when each piston is upon its suction stroke, the valve strips K will seal the ports I and as the passage G is out of registration with the port H, there is no communication to the space within the cylinder above the piston. Therefore, the movement of the piston will create a partial vacuum until the passage G registers with the port H, whereupon the gas to be compressed will be drawn in through said port and passage and will fill the cylinder. Upon the reverse stroke the

passage G and port H pass out of registration, after which a further movement of the piston will compress the gas until a pressure is reached which is higher than the pressure in the outlet. When sufficiently high, the pressure in the cylinder will force the valve strip K from its seat, bowing it upward into the segmental recess J and permitting the compressed gas to pass outward. It will be noted, however, that the area exposed to pressure outside of the cylinder is greater than the area of the port I, so that a considerably higher pressure will be attained within the cylinder than that outside thereof before the valve will open.

What I claim as my invention is:

1. A pump including an open ended cylinder having a gas inlet port in a side wall thereof, a head for the cylinder having a discharge passage therein, a plate between said head and cylinder having a port in communication with said passage constituting the sole outlet for gases from said cylinder, a normally seated noiseless valve in the head for controlling the flow of gases through said outlet port, and a piston in the cylinder adapted to compress the gases admitted through said inlet port and thereby cause said valve to be unseated, said piston being so constructed and arranged as to uncover said inlet port upon its suction stroke and cover the said port upon its compression stroke, thereby providing a noiseless control for said inlet port.

2. A pump including a cylinder having a gas inlet port in a side wall thereof, a head having a discharge passage therein, a plate between said head and cylinder having a port in communication with said discharge passage constituting the sole outlet for gases from the cylinder, a substantially noiseless control for the inlet port comprising a piston in the cylinder consisting of a solid body having a passage therethrough adapted to register with said inlet port at the completion of its suction stroke, and means for controlling the flow of gases through the outlet port comprising a noiseless valve in the head adapted to be seated automatically when the piston is on its suction stroke and adapted to be unseated automatically by the pressure of gases in the cylinder when the piston is on its compression stroke.

In testimony whereof I affix my signature.

THOMAS C. WHITEHEAD.
